[57] **CLAIM**

The ornamental design for a printer with automatic sheet feeder, substantially as shown and described.

DESCRIPTION

FIG. 1 is a front, left perspective view of the printer with automatic sheet feeder showing our new design;

FIG. 2 is a right rear perspective view thereof;

FIG. 3 is a top plan view thereof on an enlarged scale;

FIG. 4 is a front elevational view thereof on an enlarged scale;

FIG. 5 is a rear elevational view thereof on an enlarged scale;

FIG. 6 is a right side elevational view thereof on an enlarged scale;

FIG. 7 is a left side elevational view thereof on an enlarged scale;

The bottom of the printer is unornamented.
